CLAIM

The ornamental design for goggles, as shown and described.

DESCRIPTION

FIG. 1 is a perspective view of goggles of the design; FIG. 2 is a top plan view of the design shown in FIG. 1;

FIG. 3 is a front elevation view of the design shown in FIG. 1;

FIG. 4 is a rear elevation view of the design shown in FIG. 1;

FIG. 5 is a bottom plan view of the design shown in FIG. 1; and,

FIG. 6 is a side elevation view of the design shown in FIG. 1, the side opposite being a mirror image.

The broken line showing of the strap in FIG. 1 is for illustrative purposes only and forms no part of the claimed design.
